UNITED STATES PATENT OFFICE.

JAMES J. O'CONNOR, OF WHITE MILLS, PENNSYLVANIA, ASSIGNOR TO
C. DORFLINGER & SONS, OF SAME PLACE.

DESIGN FOR A GLASS VESSEL.

SPECIFICATION forming part of Design No. 22,581, dated July 4, 1893.

Application filed February 16, 1893. Serial No. 462,637. Term of patent 14 years.

To all whom it may concern:

Be it known that I, JAMES J. O'CONNOR, a citizen of the United States, residing at White Mills, in the county of Wayne and State of Pennsylvania, have invented and produced a new and original Design for the Ornamentation of Glass Vessels, of which the following is a specification, reference being had to the accompanying drawing, which is an elevation 10 of a glass vessel, such as a "rose-jar," showing the design applied thereto. In this figure the vessel is shown with only a part of its surface covered with the design; but it is obvious that the design is intended to be continued entirely around the vessel.

The main feature of my design consists in the novel grouping and arrangement of diamond-shaped, triangular-shaped and fan-shaped figures which form the pattern, a more 20 detailed description of which is as follows:

R, R, are diamond-shaped figures, arranged side by side, and having their surfaces covered with the intersecting lines a, a , as shown in the drawing. Surmounting each of the

diamond-shaped figures R, R, is a fan-shaped 25 figure F. The diamond-shaped spaces, between the fan-shaped figures F, F, and the upper sides of the diamond-shaped figures R, R, are each divided into two parts by the intersecting line T; the upper part B is filled 30 with the intersecting lines t, t , which are much closer together than the lines a, a , on the figures R, R, as shown in the drawing; the lower part C is plain. Each of the quadrilateral spaces inclosed between the lower sides of the 35 diamond-shaped figures R, R, and the lines H, H, are divided into two triangular spaces, by the intersecting line N. The surfaces of both the said triangular spaces, E, K, are plain. 40

What I claim is—

The design for the ornamentation of glass vessels, substantially as herein shown and described.

JAMES J. O'CONNOR.
